(57) CLAIM

The ornamental design for a wall hanging rack as shown and described.

DESCRIPTION

FIG. 1 is a perspective view of a wall hanging rack showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is a partial enlarged view of FIG. 1 thereof; and,

FIG. 10 is a partial enlarged view of FIG. 2 thereof.

The dash-dash broken lines illustrate portions of the wall hanging rack that form no part of the claimed design. The dash-dot broken lines in FIGS. 1, 2, 9 and 10 demarcate enlarged areas and form no part of the claimed design.

1 Claim, 10 Drawing Sheets
